United States Patent Office

Des. 223,773
Patented June 6, 1972

223,773

VACUUM CLEANER

Karl Hugo Lindstrom, Sollentuna, Sweden, assignor to
Aktiebolaget Electrolux, Stockholm, Sweden

Filed Feb. 3, 1971, Ser. No. 112,508

Claims priority, application Sweden Aug. 10, 1970

Term of patent 14 years

Int. Cl. D15—05

U.S. Cl. D49—14

FIG. 1

FIG. 2

FIG. 3

FIG. 4

FIG. 5

FIG. 1 is a front perspective view of a vacuum cleaner showing my design;

FIG. 2 is a front elevational view thereof;

FIG. 3 is a side elevational view thereof;

FIG. 4 is a rear elevational view thereof; and

FIG. 5 is a top plan view thereof.

The broken lines on the electric cord indicates indeterminate length.

I claim:

The ornamental design for a vacuum cleaner, as shown and described.
